UNITED STATES PATENT OFFICE.

HARRY L. GURLEY, OF MARION, OHIO.

CUT-OUT FOR DOWN-SPOUTS.

1,274,536.

Specification of Letters Patent.

Patented Aug. 6, 1918.

Application filed July 27, 1916. Serial No. 111,704.

To all whom it may concern:

Be it known that I, HARRY L. GURLEY, a citizen of the United States, residing at Marion, in the county of Marion and State of Ohio, have invented certain new and useful Improvements in Cut-Outs for Down-Spouts, of which the following is a specification.

This invention relates to cut outs for down spouts, and aims primarily to provide a mechanism within the down spout which normally maintains the same in communication with an outlet or waste pipe, and at the same time severs its connection with the cistern or other reservoir, and which is capable of automatically actuating after a certain amount of water has passed through the down spout to close communication with the outlet and to establish communication between the down spout and the cistern.

A further object of the invention is to provide an automatically operated mechanism for establishing communication between a down spout and cistern or other reservoir after a certain amount of water has passed through the down spout.

A still further object of the invention is to provide a device of this character, which is provided with improved means for normally resetting the mechanism to initial position after the water has ceased to flow through the down spout.

A still further and particular object of the invention is to provide a device of the above mentioned character, which is of simple and inexpensive construction, which is composed of but few readily assembled parts, all so constructed and arranged as to minimize the opportunity for wear, breakage or derangement, the various operations of which are automatic, which requires no attention after once being installed, and which will prove thoroughly practical and efficient in the attainment of the ends for which it is designed.

With these objects in view, together with others which will appear as the description proceeds, the invention resides in the novel formation, combination and arrangement of parts, all as will be described more fully hereinafter, illustrated in the drawings, and particularly pointed out in the claim.

The invention will be best understood by referring to the accompanying drawings, wherein:

Figure 1 is a fragmentary elevation of a

conventional form of down spout, illustrating the application of a cut out spout mechanism constructed in accordance with my invention, parts of the apparatus being shown in section;

Fig. 2 is a vertical sectional view taken substantially upon the line 2—2 of Fig. 1;

Fig. 3 is a vertical sectional view taken through the down spout and illustrating the valve therein;

Fig. 4 is an enlarged horizontal sectional view taken on line 4—4 of Fig. 2;

Fig. 5 is a vertical sectional view taken on line 5—5 of Fig. 4.

The invention comprehends broadly the arrangement of a valve in the down spout capable of establishing communication between the down spout and any one of a plurality of branch pipes, a movable member for actuating the valve to sever the connection between the down spout and one of the pipes and open communication between the down spout and another of the pipes, and a feed pipe for directing water from the down spout to the movable member to actuate the latter to operate the valve. The invention further consists in improved means for draining the water from the movable member so that the same may resume initial position after the water has ceased to flow through the down spout. The invention further resides in the detail construction to be hereafter referred to.

Referring now more particularly to the drawings, 6 represents a down spout leading from a gutter or roof of a building, and through which rain water is adapted to flow. This spout is forked adjacent its lower end, providing branch pipes 7 and 8, the former being directed into a cistern or other reservoir (not shown), while the latter constitutes an outlet to be connected with a sewer system or the like. Arranged at the junction of the branch pipes 7 and 8, with the down spout 6, is a valve or gate 9, the latter being mounted for oscillation within the pipes upon the stem or shaft 10. The construction and arrangement of this valve is such as to open or close communication between the said branch pipes and down spout 6.

The stem 10 projects beyond the water pipes and is supported adjacent its outer end within a suitable bracket 11. The extremity of the shaft or stem may be squared as shown for engagement within a similarly

shaped opening in a valve operating lever 12.

Arranged adjacent one of the branch pipes and below their connection with the 5 down spout is a movable member in the form of a tank, or container 13. This container is connected at its upper end by means of links 14 with the rear end of the lever 12, the said lever carrying at its forward end, a weight 15 which normally over-balances the container 13. An adjusting member, such as a set screw 16 may be threaded or extended through the weight 15, whereby the latter may be adjusted toward 15 and away from the connection of the lever with the valve stem 10. The construction is such that when the lever is swung downwardly under the influence of the weight 15, the valve 9 is positioned across the branch 20 pipe 7 so as to prevent water flowing through the down pipe 6, gaining access to the cistern or reservoir. When in this position, water will be deflected into the branch or waste pipe 8. When, however, the lever 25 12 is rocked upwardly, under the influence of the tank 13, the arm 12 will rotate the stem 10 to position the valve 9 across the mouth of the branch pipe 8, whereby water flowing downwardly through the spout 6 30 will be directed into the cistern with which the branch pipe 7 communicates.

Arranged within the down spout, a short distance above the branch pipe connection is an apron 17. This apron is of substantially short duration and of cylindrical formation, being of slightly less diameter than that of the down spout throughout the major portion of its length and being provided with an annular flange portion 18 at 40 its lower end fitting snugly within the down spout. The upper end of the apron is provided with an outwardly projecting annular screen 19, the said screen preventing the entrance of solid substances to the space between the upper portion of the apron and the inner surface of the down spout 6. Communicating with the interior of the down-spout slightly above the flange portion 18 is a feed pipe 20. This feed pipe extends 50 downwardly substantially parallel with the down spout and is provided with a valve 21 whereby the passage of fluid through the said pipe may be regulated. The lower end of the feed pipe extends within the tank 13, being loosely inclosed by a sleeve 22 in the upper surface of the tank and extending downwardly into the same. In this manner, water passing through the feed pipe 20 will be directed into the tank, and the tank will 60 be permitted to move vertically upon the pipe 20 without severing or in any other way impairing the communication.

The bottom of the tank 13 is tapered downwardly toward its center as shown, and 65 is equipped with a valve or pet cock 23,

Arranged beneath the pet cock and secured to the pipe 7 by a suitable bracket member is a funnel or collector 24, which is connected at its lower end with a pipe 25 communicating with the waste pipe 8. The 70 funnel 24 is positioned so as to receive water escaping through the valve 23 and such water will be directed into the waste pipe as will be readily understood.

Secured to the pipe 7 beneath the tank 75 13 is a bracket 26. This bracket clamps the upper end of a tubular member 27, the lower end of the said member resting upon suitable shoulders formed within the upper open end of an elbow 28; the latter being in 80 communication with the pipe 7 through a pipe 29.

Secured to the tank 13 and extending upwardly through the bottom thereof is an outlet or overflow pipe 30. This pipe extends below the tank and fits loosely within the upper open end of the tubular member 27, while at its upper end it terminates slightly below the top of the tank 13. A removable cap 31 is provided upon the tank 90 to permit of access being had to the interior thereof. This construction permits of water collected within the tank overflowing through the outlet 30 and being directed through the tubular member 27, elbow 28 95 and pipe 29 into the cistern lead 7. The sliding connection between the tubular member 27 and overflow pipe 30 supports the tank against lateral swinging movement.

The cut out mechanism above described 100 is preferably inclosed by a double walled housing 32, the latter being equipped with a door 33 to permit access being had to the parts inclosed by the housing. The walls of this housing may, if desired, be filled with 105 suitable packing to prevent freezing of the inclosed parts in cold weather.

The down spout 6 is provided preferably with a removable section 34 which fits within the upper open end of the section 6 so as 110 to be capable of being readily removed therefrom when desired to limit the downward movement of the section 34, the latter being provided with an annular flange 35 to rest upon the upper edges of the section 6. 115 This construction permits of access being had to the strainer apron within the down spout 6, so that the latter may be cleaned in the event of its becoming clogged.

The operation is as follows:— 120
The tank 13 is empty and the valve 23 in the bottom thereof is open. The weight 15 on the lever 12 is greater than that of the tank 13, and consequently the shaft 10 will be maintained in the position indicated by 125 full lines in Fig. 1 of the drawings. This disposition of the valve stem adjusts the valve 9 to the position indicated in Fig. 3, the valve 21 in the feed pipe 20 is open, and rain water descending through the pipe 6 130

will be deflected by the valve 9 into the waste pipe 8. However, a small portion of the descending water will be directed through the screen mesh 19 and into the feed pipe 20. This water will eventually fill the tank 13, as the pet cock 23 has preferably a restricted outlet. As the tank fills, the weight thereof overcomes that of the weighted lever 12, and the descending tank 13 rocks the valve 9 to close the branch pipe 8 and to direct water from the down pipe 6 to the cistern pipe 7. Water continuing to flow into the tank 13 through the feed pipe 20 will be directed into the cistern pipe 7 through the overflow 30. When water ceases to flow through the down spout, the mechanism will remain in operative position until the water within the tank 13 is approximately one-half drained therefrom through the pet cock 23. Immediately then, the weight 15 overcomes the weight of the tank 13 and the remaining water therein, and the parts move automatically to initial position.

With the mechanism such as that above described, dirt, dust and other matter which may have accumulated upon the roof or in the gutters of the spouting, will be prevented from entering the cistern. The first flow of rain water will clean the roof and spouting, such water being directed into the drain pipe 8. After a certain amount of water has passed through the pipes, the mechanism operates to direct the further flow of liquid into the cistern.

While the above is a description of the preferred embodiment of the invention, it is apparent that various changes in the minor details of construction and arrangement of parts may be resorted to, if desired,

without departing from the spirit of the invention or exceeding the scope of the claim.

What is claimed is:—

The combination with a down spout having a pair of branch pipes; of a valve at the juncture of said branch pipes with said down spout and being capable of being moved to alternately establish communication between said spout and either of said pipes, a feed pipe arranged in spaced parallel relation to said down spout and communicating with the interior of the latter at its upper end above said valve, a tubular member arranged in spaced parallel relation with one of said branch pipes and being in communication at its lower end with the latter, a tank having openings in its upper and lower ends at diametrically opposite points, a sleeve communicating with the opening in the upper end of said tank slidably receiving said feed pipe, an overflow pipe in said tank extending downwardly through the opening in the bottom thereof, the said overflow pipe being engaged in said tubular member, a pipe projecting outwardly from the other of said branch pipes, a funnel on the outer end of said pipe disposed beneath said tank, a drain valve in the bottom of said tank, a lever connected to the valve in said down spout for operating the same, and a link connecting the upper end of said tank with one end of said lever, substantially as described.

In testimony whereof I affix my signature in presence of two witnesses.

HARRY L. GURLEY.
